UNITED STATES PATENT OFFICE.

EDWARD F. PINK, OF CAMBRIDGE, MARYLAND.

WIRE FABRIC.

Application filed April 37, 1926. Serial No. 773,812.

This invention relates to a woven wire fabric especially adapted for use for belts or the like, the general object of the invention being to form the fabric of helical wire members extending crosswise of the belt, with the belt composed of sections, the helical members of one section being reversely arranged to those of the other section so that the tendency of the belt to creep sidewise on the drums or pulleys is counteracted and also to so connect the sections together that the helical members of one section are in alinement with those of the other section so that an endless belt can be formed of the fabric.

Another object of the invention is to so connect the members together that the members of each section are connected together in pairs and each pair of members of one section is connected with a pair of members of the other section, thus avoiding raised parts at the center of the belt which would injure the rolls or pulleys and the material placed on the belt, and this connection of the two sections prevents sagging of the belt.

This invention also consists in certain other features of construction and in the combination and arrangement of the several parts, to be hereinafter fully described, illustrated in the accompanying drawings, and specifically pointed out in the appended claims.

In describing my invention in detail, reference will be had to the accompanying drawings wherein

The figure of the drawing is a view of portion of the fabric composed of two sections with the sections permanently connected together at their inner edges.

In this drawing the character A indicates one section of the fabric and B the other section thereof. Each section is composed of a plurality of helical wires which extend transversely of the fabric, the convolutions of each member or wire being interlocked or interwoven with the convolutions of the adjacent members. The outer and inner portions of these convolutions form diagonal ribs on the outer and inner sides of the belt, the ribs at the inner surface of the belt bearing on the supporting drums or pulleys, while the ribs on the outer surface support the articles or material being conveyed by the belt.

The helical members of one section are reversely arranged to those of the other section so that the outer and inner ribs of one section extend in an opposite direction from the outer and inner ribs of the other section. This arrangement prevents any tendency of the belt to creep sidewise on the drums or pulleys, as the members of one section tend to move in one direction, while the members of the other section tend to move in an opposite direction.

The members of each section are connected together at their ends in pairs, the outer ends of each pair of members being connected together by the eyes 2, while their inner ends are connected together by brazing, solder, spot welding, or the like, as shown at 3. The inner ends of each pair of members of one section are connected with the inner ends of each pair of members of the other section by this brazing, welding, soldering, or other process. It will also be seen from the drawing that the helical members of one section are in alinement with the members of the other section so that the ends of the fabric are straight and this permits the fabric to be formed into an endless belt. The method of connecting the inner edges of the two sections together eliminates ridges and raised places so that the central portion of the belt is smooth and there is no danger of the drums or pulleys being injured by having a ridge at the center. This method also prevents the sections from being torn apart.

From the foregoing it will be seen that by the construction shown, I have provided a fabric formed of sections which are rigidly connected together in a smooth manner so as to eliminate ridges or raised places and in which the helical members of one section are in alinement with those of the other section so that the fabric will have a smooth and unbroken inner and outer surface and the fabric will withstand an equal strain at all points; and by having its helical members straight from edge to edge of the fabric, the fabric can be formed into an endless belt and such a belt will travel in a straight line over the drums or pulleys.

It is thought from the foregoing description that the advantages and novel features of my invention will be readily apparent. It is to be understood that I may make changes in the construction and in the com-

bination and arrangement of the several parts, provided that such changes fall within the scope of the appended claims.

What I claim is:—

- 5 1. A wire fabric composed of longitudinally extending sections, each section extending the full length of the fabric, and each section comprising helical members, the diagonally arranged ribs formed by
- 10 said members extending in one direction in one section and in an opposite direction in the other section, with the helical members of one section in alinement with those of the other section, means for rigidly and
- 15 permanently uniting the ends of the helical members of each section together in pairs, and means for rigidly and permanently uniting the inner ends of each pair of mem-

bers of one section to the inner ends of the pairs of members of the other section. 20

2. A wire fabric composed of two longitudinally extending sections, each section composed of helical members extending crosswise of the section and interlocking, the members of one section being reversely arranged to those of the other section, with the members of one section in alinement with those of the other section, and means for rigidly and permanently uniting the inner ends of each pair of members of one section with the inner ends of each pair of members of the other section. 25 30

In testimony whereof I affix my signature.

EDWARD F. PINK.
